CLAIM

The ornamental design for a slingshot or similar article, as shown and described.

DESCRIPTION

FIG. 1 is a right side elevational view of a slingshot or similar article showing our new design with the broken lines showing an elastic band and pouch being for illustrative purposes only and forming no part of the claimed design;

FIG. 2 is a top plan view thereof;

FIG. 3 is a left side elevational view thereof;

FIG. 4 is a bottom plan view thereof;

FIG. 5 is a front elevational view thereof; and

FIG. 6 is a rear elevational view thereof.

FIG. 1

FIG. 2

FIG. 3

FIG. 4
